United States Patent Office

Des. 224,161

Patented July 4, 1972

224,161

HOUSING FOR A COMBINED RADIO RECEIVER AND RECORD PLAYER OR SIMILAR ARTICLE

Harvey K. McQuarrie, Kitchener, Ontario, Canada, assignor to Electrohome Limited, Kitchener, Ontario, Canada

Original design application June 15, 1970, Ser. No. 23,476. Divided and this application May 27, 1971, Ser. No. 147,713

Term of patent 14 years

Int. Cl. D14—03

U.S. Cl. D56—4

FIG. 1

FIG. 2

FIG. 1 is a perspective view of a housing for a combined radio receiver and record player or similar article, showing my new design; and

FIG. 2 is a side elevational view thereof.

Portions of the drawing figures are diagonally lined to indicate transparency.

This application is a division of my copending companion application, Ser. No. D. 23,476, filed June 15, 1970.

I claim:

The ornamental design for a housing for a combined radio receiver and record player or similar article, as shown and described.
